UNITED STATES PATENT OFFICE

149,059

DESIGN FOR A COMB HOLDER

Emery M. Hanrahan, Kenosha, Wis.

Application March 6, 1947, Serial No. 137,407

Term of patent 3½ years

(Cl. D86—10)

To all whom it may concern:

Be it known that I, Emery M. Hanrahan, a citizen of the United States and resident of Kenosha, in the county of Kenosha and State of Wisconsin, have invented a new, original, and ornamental Design for a Comb Holder, of which the following is a specification, reference being had to the accompanying drawing, forming part thereof.

I claim:

The ornamental design for a comb holder, as shown.

EMERY M. HANRAHAN.
